US00D999170S

(12) **United States Design Patent** (10) **Patent No.:** **US D999,170 S**
(45) **Date of Patent:** **** Sep. 19, 2023**

(54) **SIDE MIRROR WIND TURBINE**

(71) Applicant: **K&N Engineering, Inc.**, Riverside, CA (US)

(72) Inventors: **Jonathan Richard Fiello**, Yucaipa, CA (US); **Steve Williams**, Cherry Valley, CA (US)

(73) Assignee: **K&N Engineering, Inc.**, Riverside, CA (US)

(**) Term: **15 Years**

(21) Appl. No.: **29/696,672**

(22) Filed: **Jun. 28, 2019**

(51) **LOC (14) Cl.** **13-01**

(52) **U.S. Cl.** USPC **D13/115**

(58) **Field of Classification Search**

USPC D13/101, 114, 115, 118, 122, 184, 199; D12/344, 345; D15/1, 199, 29

(57) **CLAIM**

The ornamental design for an side mirror wind turbine, as shown and described.

DESCRIPTION

FIG. 1—Top, front, left side perspective view;

FIG. 2—Front elevation view;

FIG. 3—Rear elevation view;

FIG. 4—Left side elevation view;

FIG. 5—Right side elevation view;

FIG. 6—Top plan view; and,

FIG. 7—Bottom plan view.

Portions of the side mirror wind turbine shown in broken lines form no part of the claimed design.

1 Claim, 4 Drawing Sheets

FIG. 1

FIG. 4

FIG. 2

FIG. 5

FIG. 3
